CLOTH SPREADING DEVICE

Wendell H. Shields, Grand Rapids, Mich.

Application March 11, 1942, Serial No. 434,260

24 Claims.

(Cl. 26—55)

This invention relates in general to a spreading and feeding device for use in the textile industry wherein cloth in a long tubular form is spread into two parallel sheets and fed away from the machine to a second machine which may perform another operation thereon.

While the particular use to which this machine has been put in practice has been to receive the cloth from a dye vat and feed it to a drying machine, it is to be understood that this use as explained here is merely by way of illustration and that the cloth may be either dry or wet and it may be fed either to a drying machine or to any other place where a subsequent operation is to be performed thereon. However, for the purposes of description it will be assumed that the tube of cloth referred to has come from a dye vat, is still damp and is to be transferred to a drying machine.

In the textile industry it is common practice to weave or knit cloth in considerable lengths in a tubular form, and so it is the primary object of the present invention to provide adjustable means which will spread the tube of cloth into two closely adjacent parallel sheets and feed it in this form away from the device.

Another object of the invention is to provide means for maintaining the cloth in substantially its tubular form before it reaches the spreading and feeding means.

Inasmuch as this elongated tube of cloth as it comes from the dye vat may rest in a pile at the bottom of the machine before it is fed away therefrom, it is a further object of the invention to provide some means for maintaining the tube straight and untwisted so that the seam or wale thereon will at all times be straight.

Furthermore, since the machine to which the cloth is fed, whether it be a drying machine or other type, will have independent means thereon to positively feed the cloth through the machine, it is a still further object of the present invention to provide means whereby the rate of feeding the cloth from the spreading device may be regulated and adjusted to be synchronized with the rate of speed of the machine to which the cloth is fed so that the speed of the two feeds will be substantially the same to prevent wrinkling or stretching of the cloth.

Other objects and purposes of the invention will appear more fully as the description proceeds.

To the accomplishment of the foregoing and related ends said invention, then, consists of the

means hereinafter fully described and particularly pointed out in the claims.

The annexed drawings and following description set forth in detail certain means for carrying out the invention, said means constituting, however, but one of various forms in which the principle of the invention may be employed.

In said annexed drawings wherein like reference numerals refer to like parts throughout the various views:

Fig. 1 is a shortened side elevational view of the complete machine.

Fig. 2 is a fragmentary elevational view looking at right angles to the machine as shown in Fig. 1.

Fig. 3 is an enlarged fragmentary vertical section through the lower part of the machine.

Fig. 4 is an under plan view of Fig. 3 with a part thereof in section to more clearly disclose parts of the device.

Fig. 5 is an enlarged fragmentary, part vertical section, and part elevational view of the spreading and feeding means at the top of the machine.

25 Figs. 6, 7, 8 and 9 are sectional views taken respectively on the planes of lines 6—6, 7—7, 8—8 and 9—9 of Fig. 5, and

Fig. 10 is a fragmentary vertical section at the top of one of the concentric tubes showing the 30 device which is placed thereon while the tube of cloth is being initially placed on the machine before feeding away therefrom.

Inasmuch as the tubes of cloth are of considerable length, it is desirable to provide an elongated tube commonly known to those skilled in the art as a "can" and indicated in the drawings by the numeral 1. This can is usually some 20 or 30 feet in length and may have a diameter of some 30 inches or more. The length of this can makes it necessary for it to extend below the floor line 2 and in practice this can is provided with a collar 3 at the top end thereof provided with a flange 4 which rests on the floor 2 and suspends the can therefrom.

45 Centrally located within the can 1 are the two outer and inner concentric tubes 5 and 6 respectively, both of which extend from below the bottom of the can to a considerable distance above the top thereof. Centrally located within the inner concentric tube 6 is the elongated shaft 7 which extends both above and below either of said concentric tubes.

In the lower end of the can there is provided a bottom 8 which has a boss 9 extending downwardly therefrom and is secured to the lower

end of the outer tube 5 by means such as the screws as indicated in Fig. 3. Below the boss 9 is located a spider 10 the hub of which extends downwardly and is flanged outwardly as at 11 into two parts so that it may be clamped to the inner tube 6. A plurality of brackets 12 extend upwardly from the outer edge of the spider 10 and are secured at their upper ends to the lower end of the can 1. The boss 9 of the bottom 8 extends downwardly to the upper side of the hub of the spider 10 and is annularly recessed at that point to permit the sprocket wheel 13 to be secured thereto. It will thus be seen that a rotation of the sprocket wheel 13 will rotate the bottom 8 and outer tube 5 which is connected therewith. The can 1 and the spider 10 will not be rotated because they are clamped to the inner tube 6 and secured to the lower end of the can 1.

At one side of the machine the bracket 12a is modified slightly from the other brackets 12 and has an arm 14 extending outwardly therefrom terminating in a vertical cylindrical portion 15 adapted to have a shaft 16 pass vertically therethrough to the upper end of which is secured a universal joint 17. To this joint is secured a rod 18 which extends upwardly and, by means of a second universal joint 19 is connected to a vertical rod 20 extending upwardly through the floor and is connected at its upper end to the wheel 21. The lower end of the vertical shaft 16 is provided with a sprocket wheel 22 around which, and the sprocket wheel 13, a chain 23 passes. Thus far, it will be seen, that a rotative movement of the wheel 21 will be transmitted to the respective shafts 20 and 18 and to the sprocket wheel 22 which, by means of the chain 23, will rotate the sprocket wheel 13 and the various parts connected therewith as above mentioned.

Also clamped to the lower end of the inner tube 6 is the housing 24 which has an elongated cylindrical portion at one side and the outwardly rounded portion 25 through which the shaft 26 passes to support the fan 27 within the housing and the pulley 28. Mounted on the opposite side of the housing 24 is the platform 29 which has the motor 30 mounted thereon. The motor has a pulley 30a mounted thereon around which and the pulley 28 the belt 31 passes so that the motor 30 will drive the fan 27 for a purpose which will be more fully described hereinafter.

Mounted on the under side of the support 29 is a plate 32 which has movably mounted thereon the support 33 to which in turn is secured the motor 34. The plate 32 has on its underside a plurality of grooves 35 which receive corresponding tongues on the upper side of the support 33 so that the motor may be moved lengthwise of the plate 32, for a purpose presently to be described.

The lower portion of the cylindrical part of the housing 24 has an inside diameter such that the shaft 7 will fit snugly therein thereby forming a bearing for the lower end of said shaft. The lower end of this cylindrical part has an annular inwardly extending offset to provide a short downwardly extending portion 36 of a smaller outside diameter than the remaining cylindrical part of the housing 24. Another smaller housing which has a short upwardly extending cylindrical portion 37 and a lower enlarged portion 38 is fitted snugly around the bottom end of the housing 24 and fastened securely thereto, the upper end of the bottom housing bearing against the shoulder which is formed between the larger

and smaller portions at the bottom of the housing 24.

A worm gear 39 is secured to the lower end of the shaft 7 and within the part 38 of the bottom housing, while adjacent the worm gear is located the worm 40 mounted on the horizontal shaft 41 extending in a horizontal plane through the bottom of the housing. At one end, the shaft 41 extends outwardly a considerable distance beyond the housing and has secured to its outer end a collar 42. Spaced from said collar is a split pulley 43 adjacent the opposite side of which is located another collar 44. Between the outer collar 42 and the outer side of the split pulley 43 is a compression spring 45 so that in normal operation the spring will urge the pulley to its largest diameter.

The motor 34 has a shaft 46 extending therethrough on the outer end of which is located a pulley 47 and around which, and the split pulley 43, passes a belt 48. Thus far, then, it will be seen that the motor 34, through the belt 48 and the worm and worm gear drives 40 and 39, will rotate the shaft 7. As the motor 34 is moved longitudinally of its support 32 by means of its sliding connection therewith as above explained, either toward or away from the housing, the shaft 7 will be rotated either at a slower or faster rate of speed by the action of the split pulley.

At the outer end of the support 32 is a downwardly extending bracket 49 which has a horizontally outwardly extending arm 50 thereon having a vertically extending hub 51 through which the shaft 52 is rotatably mounted. To the lower end of the shaft 52 a beveled gear 53 is mounted in a horizontal plane which is in engagement with another beveled gear 54 located adjacent thereto in a vertical plane on the end of a threaded shaft 55. The shaft 55 is supported in the lower end of the bracket 49 and threadedly engages a bracket 56 located on the lower side of the plate 32 to which the motor 34 is directly secured. A rotation of the threaded shaft 55 through its threaded connection with the bracket 56 will move the plate 33 together with the motor 34 thereon in a direction either toward or away from the housing around the shaft 7 to thereby adjust and regulate the speed of rotation of said shaft.

The upper end of the vertical shaft 52 is provided with a universal joint 57 which is also connected to the lower end of a rod 58 which extends upwardly and is connected with a vertical rod 59 through a second universal joint 60. The rod 59 extends upwardly through the floor 2 and is connected at its upper end to the wheel 61. Rotation of this wheel will be transmitted through the rods 59 and 58 to the beveled gears and to the threaded shaft 55 to thereby regulate the speed of rotation of the shaft 7.

The upper end of the outer concentric tube 5 has resting thereon a bearing member 62 which fits snugly inside of the outer tube and has an inner diameter to snugly receive and form a bearing for the inner tube 6 as clearly shown in Fig. 5. The member 62 is flanged outwardly as at 63 at its upper side which flange rests on the upper edge of the tube 5. Immediately above the member 63 is another bearing member 64 which rests on the flanged portion 63 of the lower member and also has an inner diameter such as to form a bearing surface for the inner tube 6. A circular saucer-shaped disc 65 having a central opening therein to snugly receive the inner tube 6 is located immediately above the member 64

and may be either secured thereto or formed integrally therewith. In the flange 63 there is provided a plurality of recesses to receive the downwardly extending pins 66 which are secured to the upper bearing member 64. At a plurality of spaced apart points through the upper circular edge of the saucer-shaped member 65 there are provided means, such as the spaced upwardly extending fingers 67, within which the arms 68 may be pivotally mounted. These arms are of equal length and have a shape substantially like that shown in Fig. 5 and each has a short inwardly extending finger 69 at approximately right angles to the main part 68, and at the juncture of the two parts an opening is provided to receive pins 70, which pins extend also through the upwardly extending members 67 to thereby permit the arms 68 to pivot about said pins.

Centrally located within the disc 65 is a substantially circular ring 71, the outer periphery of which is horizontally forked to provide an annular groove 72. The free ends of the fingers 69 are received within the groove 72, and it will be obvious that a vertical movement of the ring 71 will impart a rotative movement simultaneously and in equal amounts to all of the arms 68. If the ring moves downwardly the upper ends of the arms will move inwardly, and if the ring moves upwardly the arms will move outwardly. At spaced apart points through the ring 71 vertical rods 73 pass downwardly and are secured to the saucer-shaped disc 65. Compression springs 74 are coiled around these pins 73 between the disc 65 and the ring 71 to urge said ring in an upward direction and thereby urge the arms 68 outwardly. From the description as given with respect to the connection which the arms 68 and the disc 65 have to the outer tubular member 5, it will be evident that a rotation of said tubular member will also cause a rotation of said fingers and, as will again be pointed out hereinafter, as the tube of cloth moves upwardly around the arms 68 which are in contact with the inner side thereof, a rotation of the tube 5 and the arms 68 will also impart a rotative movement to the tube of cloth so that if it comes to the arms in a twisted condition, the tube 5 may be rotated in either direction necessary to untwist the cloth and permit it to be received in a straight condition by the spreading and feeding means, which will now be described.

Near the top of the inner tube 6 a bearing member 75 is located and is secured within said tube by means of screws 76. This forms a bearing for the upper end of the shaft 7. A short rod 77 is located in alinement with and above the shaft 7 and is connected thereto by means of the coupling 78. The beveled gear 79 is secured to the upper end of the rod 77 and will be rotated by means of the coupling when a rotative movement is imparted to the shaft 7.

A housing is provided which consists of the two similar cast members 80 as shown in Figs. 5 and 7. The lower ends of these cast plates are just short of being semi-cylindrical and have an inside radius substantially equal to the outer radius of the tube 6 so that when the plates are placed together, one on each side of the upper end of the tube, they will fit snugly against the tube but will not quite meet. Spaced upwardly 70 from the bottom edge of each plate is integrally cast a part of a spider 81 which is adapted to rest upon the upper end of the tube 6. The lower end of each plate is flanged outwardly as at 80a to permit bolts to be inserted therethrough

5 to clamp the plates in place at the upper end of the tube 6. Extending inwardly from each member 80 are the bosses 82 and 82a which are cast integrally therewith so that rods 83 may be inserted therethrough. The bosses 82 on each member are longer than the ones at 82a and are of such length that when the members 80 are placed together the ends thereof will be spaced apart exposing a portion of the rods 83. On the exposed portion of each of these rods are rotatably mounted a large gear 84 and a smaller gear 85. At the central part of each face an opening is provided to receive the shaft 86 near each end of which, within the housing, is rotatably mounted a beveled gear 87 adapted to be in mesh with the beveled gear 79 secured to the top of the shaft 77. A bushing 81a is located centrally of the spider 81 to form a bearing for the upper part of the shaft 77.

Integral with each of the beveled gears 87 and on the inner side thereof are located the gears 88 which are held spaced apart by means of the spacer member 89. The two gears 84 and 85 are also integral so that a rotation of one will cause a rotation of the other. Each gear 88 is in mesh with each of the large gears 84 so that a rotation of the short rod 77 will cause a rotation of the beveled gear 79 which, in turn, will rotate the gears 87 and 88, to thereby impart a rotative movement to the gears 84 and 85. This construction will be more clearly understood by viewing Figs. 5, 6 and 7.

Two plates 90 (Figs. 5 and 7) are provided which are located within the inturned edges of each of the cast plates 80 and are secured thereto and conform substantially to the configuration of the edges of said cast plates. These plates 90 are wider than the housing members and extend beyond them at each side. At the top of each of these last named plates the slots 91 are provided which extend toward the outer edge at an acute angle to the horizontal. There are also provided four other plates 92 located in pairs at each end of the housing. Each plate is pivotally mounted at its lower end, by means of the pivot pins 93, to the plates 90 and are spaced apart a sufficient distance so that at their upper ends a pulley 94 can be mounted therebetween on the pin 95.

The lower end of each plate 92 is slotted almost vertically as at 96 and a U-shaped bracket 97 is located within the slot which has a pin 98 passing through its upper spaced apart ends. A pulley 99 is mounted between the sides of the bracket 97 on the pin 98 for rotative movement, while at the lower end of the bracket 97 it is provided with a hook 100, and a tension spring 101 is connected between said hook and the pivot pin 93 to normally draw the pulley 99 in a downward direction.

An endless belt 102 which has at its inner side a number of teeth 103, is located at each side of the housing and passes around the smaller gear 85 at each side thereof and around the pulleys 94 and 99. Each belt is mounted so that its outer run will move upwardly. The springs 101 aid in tensioning the belts 102 by pulling downwardly on the pulleys 99. It is to be noted that the pulleys 94 are so situated with respect to the plates 92 that the belts 102, in passing over the large pulley, will extend outwardly therefrom a short distance so that as cloth is passed upwardly the outer run of each belt will be able to contact the inner surface thereof and move it upwardly. The plates 92

between which the pulleys 94 are mounted have means associated therewith whereby they may be moved inwardly toward each other or outwardly away from each other in equal amounts to accommodate tubes of cloth having different diameters. It is necessary at all times that, as the cloth moves upwardly over the spreading means, the belts bear against the inner sides of the cloth with sufficient force to form the two parallel sheets closely adjacent each other, but without stretching the cloth, and to insure that tubes of cloth having different diameters will be spread an amount commensurate with its diameter and fed away from the machine, and for this reason it has been necessary to provide these adjusting means. This is also the prime reason for the tension springs 101 which constantly exert a downward pull on the lower pulleys 99. When the plates 92 are moved outwardly a greater tension will be placed on the springs, and likewise when they are moved inwardly, the springs will eliminate any slackness which may tend to occur in the belts.

In one of the housings 80 and centrally located with respect thereto there is provided an elongated vertical slot 104, and in the other housings 80 and opposite the slot 104 there is provided a plurality of vertically spaced apart openings 105. Links 106 are provided which are connected together at their lower ends by means of the pin 107 which extends through openings therein and through the openings 105 and the slot 104. The outer end of the pin is provided with a handle 108 and has along its length between the housings 80 a compression spring 109 which bears at one end against one of the links 106 and at its other end against a washer 110 (Fig. 6). The other end of each link 106 is slidably mounted by means of pins 111 to move longitudinally in the slots 91. The pins 111 also pass through openings provided for that purpose in the plates 92 and when the upper ends of the links 106 are moved, the plates 92, together with the pulleys thereon and the belt, are also moved. To accommodate tubes of cloth of the largest diameter the pin 107 will be moved upwardly and inserted through the topmost opening 105 at which point the links will have been spread apart at their upper ends to move the plates 92 and the pulleys 94 away from each other outwardly. Conversely, when the smallest tube of cloth is to be operated upon, the pin 107 will be moved to its lowermost position at the bottom opening 105 to move the pulley 94 inwardly toward each other.

It is significant that the spreading and feeding structure is made integral so that it may be lifted bodily and removed from the top of the outer tube 5. When this part of the device has been removed from the machine, the spreader arms 68 and the structure integral therewith may also be removed from the concentric tubes to permit the tube of cloth to be initially passed thereover to rest at the bottom of the can 1. Inasmuch as the cloth, when coming from the dye vat, will be damp and rather hard to handle it becomes advisable to place over the top of the inner tube 6 a cap somewhat like that shown in Fig. 10. This cap has a rounded upper surface 112 which is concave at its central portion as at 113. The cap is preferably of circular form and has a bottom 114 thereon spaced downwardly from the top in the form of a flange and has integral therewith a central circular portion 115 with an annular shoulder on its in-

ner surface substantially the same diameter as the tube 6 so that it will fit snugly over the top thereof. A plurality of spacer members 116 are vertically located beneath the top 112 and separate the bottom 114 therefrom. This cap, being hollow, will permit air to be forced upwardly therethrough which will escape radially through the space between the top and bottom thereof.

Operation

The operation of the device is substantially as follows. When the tube of cloth, indicated at 118, initially comes from the dye vat, the spreading and feeding device and the spreader arms will have been removed from the upper ends of the concentric tubes 5 and 6 and replaced by the cap shown in Fig. 10. The motor 30 is then started which operates the fan 27 so that a blast of air, either hot or cold, will pass upwardly through the tube 6 and radially outwardly through the cap on top thereof. The tube of cloth is then passed downwardly over the cap and the concentric tubes within the can, the air aiding in preventing the sides of the damp tube of cloth from sticking together and facilitating the initial placement of the cloth within the can for its removal therefrom.

After the tube of cloth has been entirely placed around the concentric tubes and within the can, the cap is then removed and the saucer-shaped disc 65 together with its associated parts is placed in position to rest on the upper edge of the outer tube 5 and the spreading and feeding device is located over the inner tube 6 all as clearly shown and described with respect to Fig. 5.

Assuming that the cloth is to be fed to another machine which is to perform a subsequent operation thereon, such machine may be provided with a plurality of rollers 117 which have their own driving means to independently feed the cloth to the other machine. The motor 34 will then be started which, through the worm and worm gear 40 and 39, will rotate the shaft 7. This will cause in turn a rotation of the beveled gear 79, the beveled gears 87, the gears 88 which are integral therewith, the gears 84 and 85, and the belts 102. As before described, in order that the speed of feed away from this machine can be synchronized with the speed of feed of the machine to which it is fed, an operator may rotate the wheel 61 to move the motor 34 toward or away from the vertical shaft at the bottom of the machine to vary the speed of movement of the belts 102.

The upper end of the tube of cloth will then be brought upwardly around the spreader arms 68 which, by reason of their connection with the ring 71 and the compression springs 74, will accommodate a tube of cloth of any diameter, within predetermined limits, and will maintain it in a tubular form as it moves upwardly thereover. The cloth is then moved upwardly to the belts 102 which will have previously been regulated to accommodate the particular size tube of cloth to spread it into two parallel sheets and feed it away from the machine to the rollers 117.

It will be evident that since the cloth is initially placed in the device in a haphazard manner, it may have become considerably twisted and it becomes necessary to provide means to maintain the cloth in a straight and untwisted condition as it is fed to the rollers 117. The details of this mechanism have previously been described and may be controlled by operating the wheel 21

which may cause a rotation of the disc 65 and the spreader arms 68 connected therewith. Since these arms bear outwardly against the inner surface of the tube of cloth, a rotation thereof in either direction will cause a similar rotation of the cloth and such continuous regulation will maintain it in an untwisted condition as it is fed to the spreading and feeding means and away from the machine.

From the foregoing description it will be evident that I have conceived novel means for use in the textile industry for handling cloth in tubular form as it passes from one machine to another. As above stated, in this particular instance I have described the invention, for purposes of illustration, as handling the cloth as it comes from a dye vat in a damp condition and as it is fed to a drying machine. While it has been operated satisfactorily in practice on these particular machines, it is conceivable that the cloth may be fed away therefrom to other machines which may perform other operations thereon.

Other modes of applying the principle of my invention may be employed instead of the one here explained, change being made as regards the mechanism herein disclosed provided, however, that the means stated by any of the following claims or the equivalent of such stated means be employed.

I, therefore, particularly point out and distinctly claim as my invention:

1. In a tubular cloth spreading and feeding device, the combination of an elongated tubular can, a support from which said can is suspended, outer and inner concentric tubes located within said can longitudinally thereof and extending from below the bottom to above the top thereof, the inner tube terminating above said outer tube, a bottom for said can rotatably mounted thereon and secured to said outer tube, a plurality of arms located atop said outer tube and extending radially outwardly therefrom, said tube of cloth adapted to pass upwardly within said can and around said arms, a pair of endless belts located atop said inner tube in a vertical plane at diametrically opposed points, means for moving the outer run of each belt upwardly to thereby spread the tube of cloth and feed it away from the machine, and means for rotating said bottom, outer tube and arms connected therewith whereby the cloth may be maintained in a straight and untwisted form.

2. In a tubular cloth spreading and feeding device, the combination of an elongated tubular can, outer and inner concentric tubes located within said can longitudinally thereof, said inner tube terminating above the outer one, a plurality of arms mounted adjacent the top end of said outer tube and extending radially outwardly therefrom, the outer end of each arm being substantially the same distance from the center of the tubes, a pair of endless belts mounted in a vertical plane adjacent the top of said inner tube above said arms at diametrically opposed points thereon, means to move the outer run of each belt upwardly, said tube of cloth passing upwardly around said arms which contact the inner surface of the cloth to maintain it in tubular form, and upwardly around said belts which also contact the inner surface thereof to spread it and feed it away from the device, and means connected to said outer tube to rotate said arms to thereby maintain the cloth in a straight and untwisted form.

3. In a tubular cloth spreading and feeding device, the combination of an elongated vertical

can within which the cloth is first located, inner and outer concentric tubes located centrally within said can and within said tube of cloth, a plurality of radially extending arms mounted on said outer tube, the outer ends thereof contacting the inner surface of the cloth to maintain it tubular as it passes upwardly thereover, means above said arms to spread said cloth into two parallel sheets and to move the cloth upwardly and away from the device, and means to rotate said outer tube and arms thereon as said tube of cloth moves thereover to maintain the cloth in a straight and untwisted form.

4. In a tubular cloth spreading and feeding device, the combination of an elongated vertical can within which the cloth is first located, inner and outer concentric tubes located centrally within said can and within said tube of cloth, a plurality of radially extending arms mounted on said outer tube, the outer ends thereof contacting the inner surface of the cloth to maintain it tubular as it passes upwardly thereover, and means above said arms to spread said cloth into two parallel sheets and to move the cloth upwardly and away from the device.

5. The combination of elements defined in claim 3, combined with means to vary the speed at which the cloth is fed away from the device.

6. The combination of elements defined in claim 4, combined with means to vary the speed at which the cloth is fed away from the device.

7. In a tubular cloth spreading and feeding device, spreading and feeding means comprising, a housing, two spaced apart plates secured, one at each side, to the inner edge portions of said housing, a pair of plates pivotally mounted on and between said spaced plates at each side thereof, a pulley rotatably mounted between the upper portions of each of said pairs of plates, a second pulley rotatably mounted between the lower portions of each of said pairs of plates, an endless belt located around each of said upper and lower pulleys to contact the inner side of said tube of cloth to move the cloth upwardly, and means in said housing to move said belts.

8. The combination of elements defined in claim 7, combined with means to adjust the distance apart of said first named pulleys.

9. In a tubular cloth spreading and feeding device, spreading and feeding means comprising, a housing, a pair of plates at each end of said housing spaced apart and pivotally mounted adjacent thereto, a pulley rotatably mounted at the upper end and between each pair of plates, a second pulley rotatably mounted at the lower end of each pair of plates for longitudinal movement in substantially a vertical direction, an endless belt located around the upper and lower pulleys at each end of the housing having the outer run thereof moving upwardly and contacting the inner surface of said tube of cloth to thereby move it away from the machine.

10. In a tubular cloth spreading and feeding device, comprising spreading and feeding means located within the tubular cloth and engageable with the inner surface thereof and means independent of the movement of the cloth for driving said spreading and feeding means.

11. The elements of claim 10 in combination in which the speed of said means for driving is variable relative to the movement of the cloth.

12. The elements of claim 10 in combination combined with pre-spreading means engageable

with said cloth in advance of said spreading and feeding means.

13. The elements of claim 10 in combination combined with pre-spreading means engageable with said cloth in advance of said spreading and feeding means, said pre-spreading means being adjustable relative to said spreading and feeding means in a direction rotatable of said tubular cloth.

14. The combination of elements defined in claim 10 combined with means to rotate said tube of cloth before it reaches the spreading and feeding means to maintain it in a straight and untwisted condition.

15. The elements of claim 10 in combination combined with means for positively adjusting the width of said spreading and feeding means.

16. In a tubular cloth spreading and feeding device, a belt mounted for rotation over pulleys, means for positively supporting said belt and pulleys within said tubular cloth and independent thereof with said belt in engagement with the inner surface of said cloth and means independent of the movement of the cloth for driving said belt.

17. In a tubular cloth spreading and feeding device, an elongated supporting member supported near one of its ends, a cloth spreading and feeding means mounted at the free end of said supporting member and including a belt passing over pulleys and engageable with the interior of said tubular cloth, a driving shaft extending parallel with said supporting member, means for driving said shaft and means operated by said shaft for driving said belt.

18. The elements of claim 17 in combination in which the speed of said driving means is variable.

19. The elements of claim 17 in combination combined with means for positively adjusting the width of said spreading and feeding means.

20. The elements of claim 17 in combination combined with a second elongated supporting member mounted concentric with said first supporting member, a pre-spreading device mounted on said second supporting member in ad-

vance of the spreading and feeding means and means for rotatably adjusting said supporting members relative to each other during operation of the machine.

5 21. The elements of claim 17 in combination combined with a pre-spreading device in engagement with the cloth in advance of said spreading and feeding means and means for rotating said pre-spreading device relative to said spreading and feeding means during operation of the machine.

10 22. The combination of elements defined in claim 17 combined with means to rotate said tube of cloth before it reaches the spreading and feeding means to maintain it in a straight and untwisted condition.

15 23. In a tubular cloth spreading and feeding device, the combination of elongated vertically disposed inner and outer concentric tubes around which said cloth passes, means on the outer tube to maintain the cloth tubular as it passes thereover, and means above said first named means mounted on the inner tube to spread the cloth into two parallel sheets and to feed said cloth upwardly including an elongated shaft located within the inner tube and extending thereabove, two endless belts located in a vertical plane at diametrically opposed points adjacent the top of said shaft, the outer run of each belt adapted to move upwardly and contact the inner surface of the tube of the cloth, means to rotate said shaft, and means connecting said shaft to said belts.

20 24. In a tubular cloth spreading and feeding device, spreading and feeding means to spread the cloth into two parallel sheets and feed it away from the machine comprising, a housing, pulleys mounted adjacent each end of said housing, a belt extending around each of said pulleys to contact the inner side of the tube of cloth, means to move said belts simultaneously, and means to rotate said tube of cloth before it reaches said spreading and feeding means to maintain it in a straight and untwisted condition.
